Attorney

UNITED STATES PATENT OFFICE.

FREDERICK MARTEN HALE, OF BROMLEY, ENGLAND.

PROJECTILE.

1,233,224.

Specification of Letters Patent. Patented July 10, 1917.

Application filed March 25, 1915. Serial No. 17,026.

To all whom it may concern:

Be it known that I, FREDERICK MARTEN HALE, a subject of the King of Great Britain and Ireland, and a resident of Bromley, 5 in the county of Kent, England, have invented certain new and useful Improvements Pertaining to Projectiles, of which the following is a specification.

This invention relates to projectiles such 10 as are described in the specification of Letters Patent of the United States granted to me and numbered 940,527—i. e., projectiles of the type in which the body of the projectile is of greater diameter than the bore of 15 the small arm or gun (hereinafter referred to as the gun) with which it is to be used and is provided with a rod adapted to extend into the barrel thereof.

According to the specification of British 20 Letters Patent granted to me and numbered 26764 of 1911, to prevent such a projectile from being accidentally exploded before it has moved sufficiently far away from the gun to avoid injury to persons in proximity 25 thereto, I provide, at the rear end of the projectile, a fan device which is adapted to be rotated by the action of the air during the flight of the projectile and to be thereby caused to lose a preventive effect on the relative 30 approach of two firing elements when the projectile has traveled to a predetermined distance from the gun, and I also provide means adapted to prevent the fan device from being rotated until the projectile 35 has received its initial movement on the discharge of the gun.

Now the present invention has for its object to provide means which may be employed in lieu of, or precautionally in addition to, those described in the last mentioned specification for preventing the rotation of the fan device until the projectile has received its initial movement on the discharge of the gun. According thereto there is provided a device comprising a suitable part, as a rod, which may be adapted to engage between adjacent vanes of the fan device, and an appliance which is adapted to fit externally on, or is otherwise secured to, the muzzle end or fore end of the gun, and is thus adapted to secure the said part thereto in such a position that, when the projectile is home on the gun ready for firing, the said part will engage with a vane of the fan device, or otherwise with the fan device, so as to prevent the projectile from becoming

armed by the rotation of the fan device until the projectile has received a sufficient initial movement to free the fan device from the aforesaid part.

The invention, which consists of the various features hereinafter defined, is illustrated by the accompanying drawings which show different examples of means according thereto.

Figures 1, 4, and 7 show respectively the manner in which three different examples are attached to a gun and used in conjunction with a projectile when the latter is in position on the gun.

Figs. 2 and 3 are a side and an end view respectively of the example shown in Fig. 1.

Figs. 5 and 6 are a side and an end view respectively of the example shown in Fig. 4.

Figs. 8 and 9 are a sectional side elevation and an end view respectively of the example shown in Fig. 7.

In each of the Figs. 1, 4, and 7, the projectile 1, which is provided at its rear end with a fan device 2 arranged and adapted to operate so as to arm the projectile after it has traveled to a predetermined distance from the gun—as, for example, in the manner described in the specification of my aforesaid British Letters Patent 26,764 of 1911—is shown mounted in position on the barrel 3 of the gun. In each case the projectile is shown provided with an inertia ring 4, which is adapted to prevent the fan device 2 from being rotated until the projectile has received its initial movement on the discharge of the gun, but which is adapted to be moved rearwardly in relation to the body of the projectile, owing to its inertia, upon the shock of discharge, so as then to allow rotation of the fan device and the subsequent arming of the projectile. Although this inertia ring 4 has been shown in each of the Figs. 1, 4, and 7 referred to above, it is to be understood that it may be dispensed with if desired, since its function is similar to that of the means which form the subject-matter of the present invention, and which, as hereinbefore indicated, may be employed in lieu of the inertia ring 4, or, as shown in Figs. 1, 4, and 7, precautionally in addition thereto.

As shown in Figs. 1, 4, and 7 of the drawings, when the projectile is in position on the gun, the fan device 2 is engaged by a rod 5 which is attached to the gun by a suitable appliance. Preferably this rod engages be-

tween adjacent vanes of the fan device, but obviously any other engagement which will prevent the fan device from turning and thereby arming the projectile may be effected—for example, the rod 5 might be arranged merely to abut against a part of the fan device so as to prevent rearward longitudinal movement thereof.

In the particular example shown in Figs. 1, 2, and 3, the rod 5 is mounted on a lug 6 formed on one branch of a spring clip 7, which is adapted to be sprung upon the muzzle end or fore end of the gun when required. For the purpose of facilitating the 15 springing of the clip upon the gun and its removal therefrom, there is formed thereon a ring piece 8 through which the finger is intended to be passed to enable a grip to be obtained upon the clip.

In the example shown in Figs. 4, 5, and 20 6, the rod 5 is provided with a screw clamp which is adapted to be firmly secured on the muzzle end or fore end of the gun when required. The two jaws 9 of the clamp are mounted on one end of the rod 5, and at the 25 side opposite the hinge the two jaws are formed with lugs adapted to be drawn together by means of a nut 10 and a screw 11 which is mounted on a pin 12 in the lug on the lower jaw of the clamp. The lug on 30 the upper jaw is formed with a slot 13 adapted to accommodate the screw 11 when it is swung about the pin 12 into such a position that the nut 10, when screwed down, will cause the sleeve 10^a to engage with the 35 lug on the upper jaw.

In the example shown in Figs. 7, 8, and 40 9, the rod 5 is attached to the gun by means of a bracket 14 into which it is screwed, and which is suitably fastened, as by means of 45 screws 15, to the stock of the gun. The bracket 14 is permanently fastened to the stock, but the rod 5 is intended to be screwed into or unscrewed from the bracket when desired.

In each of the examples shown, the rod 5 (with or without the appliance for attaching it to the gun) is readily detachable from the gun, as is preferred. It will be obvious 50 that there are many different ways of attaching the rod 5 to the gun other than those hereinbefore described, and therefore it is clear that many modifications may be made without departing from the scope of my 55 present invention.

What I claim is:

1. The combination with a gun and a projectile provided with a fan device adapted to be rotated by the action of the air 60 during the flight of the projectile and thereby caused to arm the projectile after a pre-determined number of revolutions, of means rigidly secured to the muzzle or fore end of the gun and, when the projectile is home 65 on the gun, engaging with said fan device so

as to prevent rotation thereof until the projectile has moved forward in relation to the gun.

2. The combination with a gun and a projectile provided with a fan device adapted to be rotated by the action of the air during the flight of the projectile and thereby caused to arm the projectile after a pre-determined number of revolutions, of means rigidly secured to the muzzle or fore end 70 of the gun and, when the projectile is home on the gun, engaging with a vane of said fan device so as to prevent rotation thereof until the projectile has moved forward in relation to the gun. 75

3. The combination with a gun and a projectile provided with a fan device adapted to be rotated by the action of the air during the flight of the projectile and thereby caused to arm the projectile after a pre-determined number of revolutions, of an appliance rigidly secured to the muzzle or fore end of the gun and a part rigidly secured to said appliance and, when the projectile is home on the gun, engaging with 80 said fan device so as to prevent rotation thereof until the projectile has moved forward in relation to the gun. 85

4. The combination with a gun and a projectile provided with a fan device adapted to be rotated by the action of the air during the flight of the projectile and thereby caused to arm the projectile after a pre-determined number of revolutions, of a clip secured to the muzzle or fore end of the 90 gun and a part rigidly secured to said clip and, when the projectile is home on the gun, engaging with said fan device so as to prevent rotation thereof until the projectile has moved forward in relation to the 95 gun. 100

5. The combination with a gun and a projectile provided with a fan device adapted to be rotated by the action of the air during the flight of the projectile and thereby caused to arm the projectile after a pre-determined number of revolutions, of a spring clip secured to the muzzle or fore end of the gun and a part rigidly secured to said clip and, when the projectile is 110 home on the gun, engaging with said fan device so as to prevent rotation thereof until the projectile has moved forward in relation to the 115 gun. 120

6. The combination with a gun and a projectile provided with a fan device adapted to be rotated by the action of the air during the flight of the projectile and thereby caused to arm the projectile after a pre-determined number of revolutions, of an 125 appliance rigidly secured to the muzzle or fore end of the gun and a part detachably and rigidly secured to said appliance and, when the projectile is home on the gun, engaging with said fan device so as to pre- 130

vent rotation thereof until the projectile has moved forward in relation to the gun.

7. The combination with a gun and a projectile provided with a fan device adapted to be rotated by the action of the air during the flight of the projectile and thereby caused to arm the projectile after a predetermined number of revolutions, of means detachably and rigidly secured to the muzzle or fore end of the gun and, when the projectile is home on the gun, engaging with said fan device so as to prevent rotation thereof until the projectile has moved forward in relation to the gun.

15 8. The combination with a gun and a projectile provided with a fan device adapted to be rotated by the action of the air during the flight of the projectile and thereby caused to arm the projectile after a predetermined number of revolutions, of a rod rigidly secured to the muzzle or fore end of the gun and, when the projectile is home on the gun, engaging with said fan device so

as to prevent rotation thereof until the projectile has moved forward in relation to the gun.

9. The combination with a gun and a projectile provided with a fan device adapted to be rotated by the action of the air during the flight of the projectile and thereby caused to arm the projectile after a predetermined number of revolutions, of an appliance rigidly secured to the muzzle or fore end of the gun and a rod rigidly secured to said appliance and, when the projectile is home on the gun, engaging with said fan device so as to prevent rotation thereof until the projectile has moved forward in relation to the gun.

Signed at London, this 12th day of March 1915.

FREDERICK MARTEN HALE.
